Dennis L. Rogers
ATTORNEY

UNITED STATES PATENT OFFICE.

GEORGE A. HALL, OF GRAND RAPIDS, MICHIGAN.

FOUNTAIN-PEN.

SPECIFICATION forming part of Letters Patent No. 498,514, dated May 30, 1893.

Application filed September 27, 1892. Serial No. 447,058. (No model.)

To all whom it may concern:

Be it known that I, GEORGE A. HALL, a citizen of the United States, residing at Grand Rapids, in the county of Kent and State of Michigan, have invented certain new and useful Improvements in Fountain-Pens; and I do hereby declare the following to be a full, clear, and exact description of the invention, such as will enable others skilled in the art to which it appertains to make and use the same.

My invention relates to fountain pens: more particularly to feeding devices for the same: and my object is to utilize capillary attraction and repulsion for this purpose, by the employment of a conical helical ink conducting shaft of wire, arranged within the ink reservoir and connected to the pen for feeding the same continuously and preventing too copious a flow or the gushing out of the ink around the pen: particularly when the reservoir is nearly empty: and the invention consists in the application of such a conducting shaft in such relation and in the construction, combination and arrangement of the various parts as herein-after described and pointed out in the claims reference being had to the accompanying drawings wherein—

Figure 1. is a central longitudinal section of a device embodying my invention and Fig. 2. a transverse section on the line 2 2. of Fig. 1.

A represents the barrel or ink reservoir and forms the handle of the pen. B. the pen section or nozzle, open at both ends and secured 35 to the open end of the barrel by a screw coupling in the usual manner.

C represents the pen of any ordinary pattern and is secured by plug D and wedge F. The plug D. is cylindrical near its central portion and tapers toward the ends: the front portion forming a feed tongue underlying and in contact with the split portion of the pen and having the ink channel E. extending along its entire length immediately underneath the 45 pen: its rear portion extends into the ink reservoir and forms a support and place for at-

taching the lower end of the conical helical ink conducting shaft G. the enlarging coils of which are extended into the barrel until the larger coils are in superficial contact with the interior surface of the barrel as shown in Fig. 1. In filling the reservoir I prefer to leave a space for this coil at the open end: then when in use, ink will not escape between the coils, but will follow or be attracted along the wire down on to the plug and flow out on to the pen through the channel E. thus feeding the pen continuously with an even flow sufficient for writing: while by not permitting its escape into the chamber in front of the coil the ink is kept back and not permitted to gush out upon the paper.

The plug D. may be made large enough to hold the pen in place and wedge F. dispensed with if found desirable.

65

I claim—

1. In a fountain pen, the combination with the ink reservoir, the detachable portion or nozzle, the pen holding plug, having the ink channel, and the pen, of the ink conducting 70 coil or wire, having the apex, or lower end, attached to the plug, and the enlarging coils extended into the barrel increasing in circumference until the larger coils are in superficial contact with the interior surface of the 75 barrel, whereby the ink is fed continuously to the pen and prevented from gushing out, substantially as set forth.

2. The combination with the barrel A of the ink conducting wire G having its larger 80 end extended into the barrel the outermost coils in contact with the interior surface of said barrel, the plug D having the ink channel E. wedge F, pen C and nozzle B, all arranged substantially as described and for the purposes set forth.

In testimony whereof I affix my signature in presence of two witnesses.

GEORGE A. HALL.
